Primary Examiner — Lakiya G Rogers*Assistant Examiner* — Michelle K. Lu(74) *Attorney, Agent, or Firm* — Rumit Ranjit Kanakia(57) **CLAIM**

I claim the ornamental design for a projector light, as shown and described.

DESCRIPTION

FIG. 1 is a Front Perspective view of a projector light showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof; and,

FIG. 7 is a Bottom view thereof.

The broken lines in the drawings depict portions of the projector light that form no part of the claimed design.
